UNITED STATES PATENT OFFICE.

DONALD S. BARROWS, OF ROCHESTER, NEW YORK, ASSIGNOR TO THE SYMINGTON COMPANY, OF NEW YORK, N. Y., A CORPORATION OF MARYLAND.

DRAFT RIGGING.

Application filed December 17, 1925. Serial No. 76,056.

This invention relates to draft rigging and, more particularly, to a housing adapted for holding the cushioning mechanism thereof.

5 The principal object of my invention, generally considered, is the provision of a housing for cushioning mechanism and especially cushioning mechanism involving a series of vertically arranged plates adapted for being flexed between followers or spacers with complementary curved surfaces, said housing being economically constructed and arranged for normally receiving wear on only the lower section thereof, said housing being 10 adapted for reversal when said lower section becomes worn for alternately receiving wear on the initially upper section thereof.

An object of my invention is the provision of a housing constructed with a pair of 20 opposite sides preferably formed by casting and joined by relatively light sections preferably formed of pressed steel, at least one of said sections being readily removable from the sides for inserting cushioning 25 mechanism therein.

Another object of my invention is the provision of a housing especially adapted for receiving cushioning mechanism of the Waugh type and preferably formed with 30 malleable iron sides and pressed steel top and bottom sections, said housing normally receiving wear only on its bottom section and being formed symmetrical for reversal in position to receive wear on the original 35 top section.

A further object of my invention is the provision of a reversible composite housing for cushioning mechanism, said housing preferably having two relatively inexpensive 40 pressed plate pans serving as the wear elements thereof and two side panels of malleable iron, said pans being adapted for successive use as the lower or floor portion of the housing to thereby receive substantially 45 all the wear from the cushioning mechanism and at least one of said pans being adapted for ready release from and application to the side sections of the housing.

Other objects and advantages of the invention relating to the particular arrangement and combination of the various parts will become apparent as the description proceeds.

Referring to the drawings illustrating my

invention, the scope whereof is defined by 55 the appended claims:

Figure 1 is a central longitudinal vertical section of draft rigging embodying my invention, the housing for the cushioning mechanism, however, being illustrated in 60 side elevation.

Figure 2 is an end view of the cushioning mechanism and housing shown in Figure 1.

Figure 3 is a fragmentary side elevation 65 of the housing shown in Figure 1, a portion thereof being illustrated in section on the line 3—3 of Figure 4.

Figure 4 is a partial transverse sectional view on the line 4—4 of Figure 3.

Figure 5 is a partial plan and partial sectional view on the line 5—5 of Figure 4.

Figure 6 is a plan view of a modified form 70 of draft rigging utilizing a housing constructed in accordance with my invention.

Figure 7 is a partial side elevation of a 75 modified form of cushioning mechanism housing.

Figure 8 is a transverse sectional view of 80 the modified form of housing illustrated in Figure 7.

First considering the embodiment of my invention illustrated in Figures 1 to 5, inclusive, a cushioning mechanism housing 1, constructed in accordance with my invention, is shown positioned between draft or center 85 sills 2 and enclosing or housing cushioning mechanisms 3 of any desired character. In the present instance, however, for the purpose of illustration, I have shown the cushioning mechanism of the Waugh type 90 comprising series of flexible plates 4 separated at convenient intervals by alternately arranged convex and concave spacers or followers 5 and 6, respectively. At the opposite ends of the series of plates 4 are the 95 front follower 7 and rear follower 8, the upper and lower edges of said followers on the outer surfaces thereof being notched at 9 and 10, respectively, for interlocking with the restraining flange portions 11 and 12 on the opposite ends of the upper and lower sections 13 and 14, respectively, of the housing 1.

The cushioning mechanism 3 is shown surrounded or embraced by a yoke 15, the forward ends of which are slotted for receiving draft rigging keys 16 and 17, respectively, 105 and the rear or closed end of which engages

backstop casting 18 positioned between the sills 2 and adapted for tying said sills together as well as for limiting the rearward movement of the yoke 15 and the associated 5 cushioning mechanism and housing. As is usual with Farlow two-key draft rigging, a coupler 19 is alined with and connected to the yoke 15 by means of the front key 16 which passes through registering slots therein and 10 corresponding slots in the associated draft sills 2 and cheek plates 20. In a similar manner, the rear key 17 alines the slotted follower 21 with the yoke 15 by passing through corresponding slots in said members and in 15 the associated draft sills and cheek plates, and serves for the transmission of draft forces from the slotted follower 21 to the draft sills 2 from the cushioning mechanism 3 after such forces have been delivered there- 20 to by means of the coupler, front key 16 and the associated yoke 15.

The upper and lower sections 13 and 14, respectively, of the housing 1 are preferably formed relatively light and inexpensive and 25 are connected by side panels 22 which are preferably formed as malleable iron castings. The housing in general is preferably formed symmetrical in outline so that it may be reversed in position as it will be obvious 30 to those skilled in the art that substantially all the wear occurs on the lower panel or section 14 and that the upper section 13 initially is substantially free from wear. When, however, the lower section 14 has been 35 worn as much as is permissible, the housing and associated cushioning mechanism may be bodily reversed in position so that the section 14 is uppermost and the section 13 lowermost so that the wear will then be 40 borne almost entirely by the section 13 thereby enabling the use of said housing for substantially double the normal life of such a housing if the same were not reversible. For supporting the housing and associated 45 cushioning mechanism in position, a plurality of carrier irons 23 and 24 are preferably employed and connected to the lower flanges of the associated sills in any desired manner.

50 To facilitate the assembly of the cushioning mechanism 3 in the housing 1, at least one of the sections 13 and 14 is preferably made readily removable from the side panels 22 and the other section may be securely 55 connected to said side panels as by means of rivets 25. In the embodiment illustrated, the means for connecting the section 14 to the side panels 22 comprises cooperating flange portions 26 and 27 on the sections 60 14 and 22, respectively, one of said flange sections being provided with outstanding lugs 28 and the other being provided with registering complementary apertures 29 so that when the section 14 is positioned in 65 place with respect to the side panels 22,

the lugs 28 engage in the apertures 29 for properly positioning the parts with respect to each other. For securing the flanges 27 and 28 together, U-shaped locking bars 30 may be provided and adapted for sliding 70 over the cooperating flanges 26 and 27 for securely wedging the same together. To secure such a wedging action, the locking bars may be formed slightly tapered from one end to the other and the flanges 27 and 28 provided with corresponding tapered ribs or beads 31 and 32, respectively, so that, when the locking bars are positioned in place, the section 14 is firmly secured to the side panels 22. When it is desired to release 80 section 14 from the side panels, it is merely necessary to remove the locking bars 30 by sliding them longitudinally from engagement with the flanges 26 and 27 and the rib portions 31 and 32 thereof.

The side panels 22 may be constructed of any desired form but are preferably rigidified by being panelled or corrugated as indicated at 33 and reinforced by web portions 34 and vertical ribs 35. The panels 22 are preferably decreased in weight by being provided with relatively large apertures 36 therein and the sections 13 and 14 are likewise preferably provided with apertures 37 and 38, respectively, which are adapted for 95 permitting dirt and the like to drop out of the housing when in service. Although the housing is shown used in connection with Waugh friction draft gear, yet, as is obvious, it is suitable for housing other forms 100 of draft gear. It is obvious that as the only portions of the housing which receive any material wear when in service are the relatively inexpensive sections 13 and 14 while the more expensive malleable iron panels receive substantially no wear, that when said sections 13 and 14 are worn out they may be replaced by corresponding new sections and utilized with old section 22 to form a new housing, if so desired.

Referring to Figure 6, my improved draft gear housing 1 is shown utilized with another form of draft rigging embodying a vertical yoke 39 connected with a coupler 40 by means of a key 41 extending between 115 associated sills 42. As distinguished from the draft rigging illustrated in Figure 1, the draft rigging illustrated in the present figure involves the use of front draft lugs 43 for limiting the forward motion of front follower 7 and rear draft lugs 44 for limiting the rearward motion of the rear follower 8. The housing 1 and associated draft gear 3 are shown disposed horizontally rather than vertically so that they better cooperate 120 with the vertical yoke 39.

Some of the advantages of my invention are secured by an arrangement such as shown in this figure, but it is obvious that all the benefits of reversability and renewability of 130

the sections 13 and 14 are not secured, because the plates 4 and spacers 5 and 6 not only wear on the lowermost of the panels 22, but also wear on the adjacent portions 5 of the sections 13 and 14 so that the wear is not limited to the relatively inexpensive sections 13 and 14, as in the arrangement shown in Figure 1. Except as specifically described in connection with Figure 6, the 10 construction of the housing and associated parts may be the same as that illustrated in Figures 1 to 5, inclusive.

Referring now to the embodiment of my invention illustrated in Figures 7 and 8, 15 a modified form of housing 1^a is shown in which the sections 13^a and 14^a are connected to the side panels 22^a by having the outwardly extending flanges 26^a thereof overlapped by inwardly extending flanges 27^a 20 of the panels 22^a. The panels 22^a are then secured in place by a bolt or bolts 45 extending through registering apertures 46 in the panels 22^a. The head 47 of the bolt 45 is preferably received in a recessed portion 48 25 of one of the side panels 22^a and engages the lower or inner wall 49 thereof and the opposite panel 22^a is preferably correspondingly recessed for receiving the nut 50 and washer 51 on the opposite end of the bolt 45. When assembled, as illustrated, the sections 13^a and 14^a are frictionally held in 30 position by engagement of the side panels 22^a therewith.

Although I have illustrated my improved 35 draft gear housing associated with Waugh draft gear, it is obvious that I do not wish to be restricted to such an association as my housing is suitable for use in other connections. Said housing is also suitable for use with other types of draft rigging than that involving horizontal or vertical yokes as the same may be used with draft links instead of yokes and may be used in other arrangements than that illustrated in the drawings.

45 Having now described my invention, what I claim is:

1. A draft gear housing comprising side portions and top and bottom sections, said sections having outwardly extending overlying flanges for joining them together, one 50 of said sections being readily releasable from the side sections and the other being immovably connected thereto.

2. A draft gear housing comprising cast 55 side portions formed with outwardly extending flanges at top and bottom thereof, and pressed top and bottom sections formed with webs extending, respectively, downwardly and upwardly, and formed with outwardly extending flanges on their free edges 60 overlying the flanges on the side portions, said housing being adapted for use with the sections positioned either way.

3. A railway draft rigging comprising 65 resilient elements and followers disposed to

the front and rear of said resilient elements, and a housing surrounding said resilient elements and formed with flanges retaining the follower members in assembled position, said housing comprising pans formed with 70 outstanding flanges on their free edges and adapted for alternately supporting and receiving wear from said resilient elements and followers and joined by side sections formed with flanges registering with the 75 flanges on the pans, one of said pans being rigidly connected to the side sections by means extending through the respective flanges and the other one releasably connected to the side sections by means embracing the other flanges. 80

4. A railway draft rigging comprising a series of resilient plates, follower members positioned at opposite ends of said series and arranged for flexing said plates, and a housing surrounding said plates and comprising sides, the top and bottom edges of which are outwardly flanged and connected by top and bottom sections formed with flanges registering with the flanges on the sides, certain 90 flanges of said side sections and the corresponding flanges on the engaging section being formed to interlock against relative longitudinal movement and means embracing said flanges for preventing disengagement thereof, said sections being formed with forward and rearward extensions interlocking with the followers for securing the same in position. 95

5. A draft gear housing comprising side 100 sections formed with outwardly extending flanges at top and bottom thereof and top and bottom sections formed with webs extending, respectively, downwardly and upwardly, the free edges of said webs being 105 formed with outwardly extending flanges overlying the flanges of the side portions, means for immovably connecting said side sections to one of said top and bottom sections and means for releasably connecting the other of said top and bottom sections to 110 said side sections.

6. A draft gear housing comprising side 115 sections formed with outwardly extending flanges at top and bottom thereof and top and bottom sections formed with webs extending, respectively, downwardly and upwardly, the free edges of said webs being formed with outwardly extending flanges overlying the flanges of the side portions, means for immovably connecting said side sections to one of said top and bottom sections and means for releasably connecting the other of said top and bottom sections to 120 said side sections, said means comprising a U-shaped member slidable over the engaging flanges of the sections, the free edges of said flanges being formed with beading to prevent transverse removal of the U-shaped member and one of said flanges being 125 130

formed with lug means engaging in a correspondingly apertured portion in the co-operating flange of the other section to provide an interlocking connection between said sections.

7. A draft gear housing comprising side sections formed with outwardly extending flanges at top and bottom thereof and top and bottom sections formed with webs extending, respectively, downwardly and upwardly, the free edges of said webs being

formed with outwardly extending flanges overlying the flanges of the side portions, and means for connecting said side sections to one of the other sections comprising a 15 U-shaped member slidable over engaging flanges of the sections, the free edges of said flanges being formed to prevent transverse removal of the U-shaped member.

In testimony whereof I affix my signature.

DONALD S. BARROWS.
